ELECTRIC IRON STAND

Stanley Alexander Duvall, New York, N. Y., assignor to Laura V. Ruffin, Louisville, Ky.

Application May 7, 1934, Serial No. 724,420

5 Claims. (Cl. 68—27)

The present invention relates to supports or stands for flatirons and is especially applicable to stands for electric flatirons although it is of improved usefulness with any form of iron.

5 With the use of the ordinary iron holder requiring the iron to be lifted from the board in order to place it on the holder or requiring an upward pull on the iron in order to partly overcome the weight of the iron to reduce friction 10 where the iron is slid up an incline from the board to the holder, it is impossible for the user to iron sitting down, because of this necessity for repeatedly lifting the iron or bearing up on the iron, without great fatigue due to the fact that 15 the upward pull on the iron must be exerted at at least half an arm's length. The result is that the user must stand up over the board in order to bring the shoulder of the lifting arm over the board and avoid having to reach out in lifting.

20 The present invention therefore seeks to provide an iron stand the use of which requires substantially no upward pull on the iron and offers a minimum resistance to movement of the iron onto and off of the stand. This object is accomplished in the main by the provision of an anti-friction support for the iron together with an anti-friction guide for guiding the iron up onto the support.

A further object of the invention is to provide 30 simple and effective means for holding the stand on an ironing board enabling the stand to be used on any standard, covered and padded ironing board without the use of elaborate clamping means or positive fastening means such as screws 35 or the like.

This object is accomplished through the provision of pointed anchor pins carried by the stand and arranged to extend down through the padding of the ironing board into engagement with 40 the board so as to resist lateral relative movement between the stand and the board. Very slight penetration of the board by the holding pins is amply sufficient to hold the stand against sliding, because of the substantially negligible, frictional 45 resistance offered to movement of the iron onto the stand and because the striking of the iron against the back of the stand occurs only when the weight of the iron and the weight of the arm of the user are exerting a downward pressure on 50 the anchor pins.

A further object is to provide a stand capable of conserving the heat of the iron while not in use or, in the case of an electric iron, while being heated, and capable of effectively insulating the 55 heat of the iron from the ironing board, without

subjecting the polished surface of the iron to rubbing contact with portions of the stand and with substantial elimination of any tendency of the iron to stick to the stand.

It has been observed in practice, especially in the case of electrically heated irons, that the iron has a tendency to stick to the surface of a support with slight though sufficient adherence to appreciably retard the sliding of the iron off the support, and that even with anti-friction supporting members in the form of rollers of extended area, there is an appreciable tendency to stick. The present invention overcomes this tendency by the use of a novel arrangement of anti-friction bearing members with relatively small area of contact with the surface of the iron.

Other objects and advantages of the invention will be apparent from a reading of the following specification with reference to the drawings accompanying the same.

In the drawings, Fig. 1 is a plan view of a preferred form of the invention.

Fig. 2 is a side view of Fig. 1 partly in longitudinal section.

Fig. 3 is a section on the line 3—3 of Fig. 1. 25

Fig. 4 is a plan view of a modification.

Fig. 5 is a side view of Fig. 4.

Fig. 6 is a section on the line 6—6 of Fig. 4. 30

Referring to the drawings in detail, and first to Figs. 1 to 3, the invention is here shown embodied in a stand for holding an electrically heated iron of the cordless type and it is therefore provided with a housing 1 at the rear end, housing a suitable jack or electric connecting socket (not shown) with which suitable plug contacts 2 carried by the iron 3 are arranged to engage for the purpose of supplying current to the iron while at rest on the holder. The holder comprises a base member 4 in the general form of an inverted shallow pan with a pair of guide flanges 5 extending upwardly along each side suitably spaced to act as guides to guide the iron 3 (shown in dotted lines) into position on the stand to bring the plug contacts 2 into proper engagement with the connecting jack in the housing. Roller bearing supporting members 6 and 7 are mounted above the top surface of the base member 4 between the guide flanges 5 and journaled on spindles 8—9 respectively, mounted in the guide flanges and extending transversely of the length of the stand. An additional guide roller 10 is mounted transversely of the stand near the leading edge and close to the lowermost portion thereof, on spindles 11 which in turn are mounted in 50

55

upstanding side lugs 12 carried by the base member 4.

The roller bearing supports 6 are arranged in a plane substantially parallel to the base member so as to provide a substantially level roller bearing support for the iron 3 spaced above the base member of the stand. These rollers 6 form the sole direct support of the iron while the latter is resting on the stand. The rollers 9-10 5 are guide rollers arranged at lower levels to guide the iron from the surface 13 of an ironing board up onto the supporting rollers 6. In Fig. 3 a portion of the ironing board is shown in section. Here the board is shown as a covered and padded 10 board, a portion of the board being indicated at 14 while the padding is indicated at 15 and the cover cloth at 16. As will be clear from Fig. 2, the guide rollers 9-10 lie below the level of the 15 top surfaces of the supporting roller 6 and are arranged with their upper bearing surface in an inclined plane sloping downwardly from the elevated horizontal plane in which lie the top surfaces of the supporting roller 6. The leading edge or front edge portion 17 of the base member 15 20 board 4 slopes down to the surface of the ironing board with the front guide roller 10 partly countersunk therein so as to bring the upper surface of the roller as near as possible to the level of the surface of the ironing board. To enable the heel 25 of the iron to be pushed up over the roller 10 without having to lift the iron, the heel of the iron is beveled upwardly and outwardly from its lower surface as indicated at 18 in Fig. 2. To ensure rolling of the various roller supports 6 and 30 guide rollers 7 and 10 with the movement of the iron thereover, that portion which contacts with the iron is made of a greater radius than that of the spindles, and to reduce to a minimum any 35 tendency of the iron to stick to the roller support 40 6, their length of contact with the iron is made relatively small, for example less than one-half the width of the iron as shown in Fig. 1.

The spindles 8 are mounted at one end in one of the guide flanges 5 directly in small openings 45 19 while the other ends of the spindles are mounted in bushings 20 threaded into large openings 21 in the other guide flange, the opening 21 being of sufficient diameter to permit the spindles with their rollers to be inserted there- 50 through in assembling. Preferably the spindles are stationary with the roller 6 arranged to rotate freely thereon, although it is obvious that if desirable the spindles may be rotatably mounted in the guide flanges 5 with the rollers either 55 fixed to the spindles or rotatably mounted thereon. Similarly, the roller 7 is preferably mounted on its spindle 9 which passes all the way through the roller 7 and is mounted at each end in open- 60 ings 22 in the guide flanges 5.

To conserve the heat in the iron while resting on the stand and to insulate the heat of the iron from the ironing board the lower surface of the stand is provided with an insulating shield in the form of a plate 23 of asbestos or equiva- 65 lent heat insulating material secured to the bottom of the stand by threaded fasteners 24 as shown in Figs. 2 and 3. The thickness of the insulating plate 23 is so proportioned in relation to the spacing of the bottom of the holder from the board so as to leave an air space between the plate 23 and the board which together with the air space between the stand and the bottom surface of the iron and the plate 23 acts to effectively 70 insulate the iron from the board to prevent 75 scorching of the board and to conserve the heat

of the iron while the latter is resting on the stand.

Because of the negligible amount of frictional resistance offered to the sliding of the iron up onto the stand and along the stand over the roller supports against the housing 1, very slight anchorage of the iron on the board is necessary to prevent the stand from sliding along the board each time the iron is moved onto or off the stand. It is therefore necessary to provide only a slight 10 anchorage between the stand and the board and this is effected by the provision of a pair of anchor pins 25 carried by the stand and ar- 15 ranged to have their pointed ends 26 forced downwardly through the padding 15 into slight pene- trating engagement with the body material of the ironing board, as shown in Figs. 2 and 3.

The anchor pins 25 are threaded as indicated in Figs. 2 and 3 and are mounted in threaded bores 26 in enlarged portions 27 of the side flanges 20 near the rear of the stand. The anchor pins may thus be moved up and down with relation to the stand by turning them in the threaded bore. To facilitate such adjustment the pins are provided with knurled heads 28 for turning them in the 25 threaded bore 26, the pins being frictionally held in adjusted position by means of friction springs 29 mounted in compression between the bottoms of the knurled head members 28 and the body of the stand. By so mounting the anchor pins 30 they may be normally retracted into the holder when not in use so as not to mar the surface of any object on which the holder may be rested and may be readily adjusted downwardly to pene- 35 trate any thickness of padding and make positive 40 penetrating engagement with the ironing board when in use. This method of holding the stand against sliding movement on the board has been found vastly more effective than some of the known methods of simply roughening the bottom 45 of the holder or providing it with a plurality of short fixed teeth or serrations for engagement with the cloth or padding of the ironing board. In those methods of holding the stand excessive wear is put upon the cover and padding with ex- 50 treme likelihood of tearing the covering and padding. With the present method of holders it will be clear that no strain or wear is put upon the covering or padding inasmuch as the points make a clear penetration of the padding and establish 55 a positive engagement with the body of the iron- board. As the forces tending to slide the stand along the board are taken in sheer by the anchor pins but slight penetration is necessary to render them very effective for the purpose intended.

In operation, the stand is placed on the ordinary covered and padded ironing board in a convenient position and the knurled heads 28 of the anchor pins turned to adjust the anchor pins 60 downwardly through the covering and padding of the ironing board into slight penetrating engagement with the board. After proper adjustment, the pins remain in the adjusted position due to the binding effect of the friction springs 65 29 which are tensioned to press upwardly on the bottoms of the knurled heads 28. The weight of the iron and holder together with some down- 70 ward pressure exhausted by the user in moving the iron onto and off of the stand, maintain firm 75 engagement of the anchor pins with the board. With the iron 3 resting on the stand as indicated in dotted lines in Fig. 2 the heat of the iron is conserved and insulated from the board by the asbestos plate 23, the air space between the bot- 75

tom of the iron and the holder, and the air space between the bottom of the iron and the board. As the roller bearing supporting members 6 support the iron in a substantially level position, and as the guide rollers 7 and 10 are arranged in a plane sloping toward the board, the user may slide the iron off the holder onto the board with a minimum of effort. In returning the iron to the holder the user has simply to slide the heel 10 of the iron against the roller 10 at the leading edge of the stand whereupon the cam action between the beveled rear edge 18 of the heel of the iron and the roller 10 will cause the iron to ride up onto the roller 10 and then up onto the rollers 9 and 6 without the necessity of the user having to lift the iron from the board to place it on the holder or even to bear upwardly on the iron to reduce the frictional resistance to the sliding movement. Thus very little force need be exerted in sliding the iron up onto the stand and what little force is necessary is applied substantially wholly in a lateral direction and is therefore effectively resisted by the points of the anchor pins.

It is known to provide an iron stand with a ramp or inclined surface or beveled extension at the leading edge of the stand to enable the iron to be slid up onto the stand without having to lift the iron clear of the board, but due to the frictional resistance against the sliding of the iron onto the holder the user feeling this resistance to the sliding movement unconsciously pulls up on the iron to reduce the friction, which upward pull or lift on the iron must be so nearly as great as that necessary to raise the iron off the board as to tire the user substantially as much as if he had to raise the iron each time it were placed on the stand.

The present invention by its elimination of the necessity for the user having to exert any appreciable lifting force on the iron, enables the user to iron while sitting down instead of having to stand up in order to position the shoulder of his lifting arm over the board. In the use of the present invention there is substantially no vertical stresses on the arm of the user, the necessity for lifting being obviated and the necessity for pressing down being in large degree eliminated by proper weighting of the iron.

In the modification shown in Fig. 4, the holder comprises a flat top portion 30 having a pair of guide flanges 31 and a rear flange 32 extending upwardly from the top plate 30. The top plate 30 is provided with a downwardly sloping front edge portion 33. A bottom plate 34 is arranged below the top plate 30 and held in spaced relation thereto by a plurality of spacer posts 35, the rear edge of the bottom plate being provided with a downwardly turned flange 36 which together with the downwardly sloping front edge 33 of the top plate act to support the holder with the bottom plate 34 spaced above the surface 37 of the ironing board. Anti-friction supporting members 38 and 39 in the form of ball-bearings are mounted in pairs of registering openings 40 and 41 respectively in the upper and lower plates, the openings being smaller in di-

ameter than the ballbearings with at least the openings in the upper plate sufficiently large to permit the ballbearings to project therethrough beyond the top surface of the upper plate so as to support the iron in spaced relation to the upper 5 plate. The ball bearings 38 are arranged as shown in Figs. 5 and 6 with their top surface in a substantially horizontal plane so as to form a horizontal, anti-friction support for an iron, while the ball bearing 39 at the leading edge of 10 the stand is positioned in a lower plane in close proximity to the level of the ironing board, being mounted between the plates in a lower portion of the downwardly sloping, forward edges of the top and bottom plates, its purpose being to act 15 as an anti-friction roller-cam and guide enabling an iron to be slid up onto the holder without having to be lifted bodily from the ironing board.

The use of this modified form of holder is similar in all respects to that of the preferred 20 form shown in Figs. 1 to 3, the roller bearing supporting member acting to enable the iron to be slid onto and off the holder with minimum expenditure of energy and substantially eliminating any tendency of the iron to stick to the 25 support because of their reduced area of contact between the ballbearing supports in the iron. It is to be understood of course that in the modification of Figs. 4 to 6, anchor pins such as the anchor pins 26 of Figs. 1 to 3 may be used with 30 equal effectiveness.

While I have thus shown and described certain specific embodiments of the invention for the sake of disclosure, it is to be understood that the invention is not limited to such specific 35 embodiments but contemplates all such modifications and variations thereof as fall fairly within the scope of the appended claims.

What I claim is:

1. In an iron stand, the combination of means 40 for reducing the frictional resistance to movement of an iron over the stand, and anchor pins carried by the stand.

2. An iron stand adapted to rest upon a padded ironing board comprising a base member, anchor 45 pins carried by the base member and means for adjusting said anchor pins vertically with respect to said base member.

3. An iron stand adapted to rest upon an ironing board comprising a base member, anchor 50 pins carried by the base member and means to adjust the anchor pins, said means for adjusting said anchor pins comprising a bolt, the head of said bolt being knurled, and a spring mounted in compression between the bottom of said 55 knurled head and the body of the stand, to maintain adjustment of said anchor pins.

4. An iron stand for use upon an ironing board comprising a base, anchor pins carried by the base, and means for projecting and retracting 60 said anchor pins with respect to said base member.

5. An iron stand for use upon an ironing board comprising a base, anchor pins carried by the base, and means for retracting said anchor 65 pins within said base member.

STANLEY ALEXANDER DUVALL.
